Inventor:

Bryant D. Pinkney.

UNITED STATES PATENT OFFICE.

BRYAN D. PINKNEY, OF CINCINNATI, OHIO, ASSIGNOR TO HUGO JABURG, JOHN JABURG, AND HENRY K. JABURG, COMPRISING THE FIRM OF JABURG BROS., OF NEW YORK, N. Y.

MECHANICAL MOVEMENT FOR DOUGH-HANDLING MACHINES.

1,310,711.

Specification of Letters Patent. Patented July 22, 1919.

Application filed November 6, 1918. Serial No. 261,321.

To all whom it may concern:

Be it known that I, BRYAN D. PINKNEY, a citizen of the United States, residing at Cincinnati, in the county of Hamilton and State of Ohio, have invented a new and useful Mechanical Movement for Dough-Handling Machines, of which the following is a specification.

My invention relates to that type of mechanical movements which are applicable to dough-handling machines such as disclosed in Patent Nos. 986,413 and 993,138; and its object is to provide a mechanical movement for imparting a plurality of oscillations or "punches" to one rotation of a punching disk or member which handles or rounds up the dough that is simple, positive, and efficient.

I attain this object by the mechanism illustrated in the accompanying drawing, in which—

Figure 1 is a plan view of my mechanical movement; Fig. 2, a vertical transverse section.

Referring to the drawing, 1 is the frame of a machine in which I have shown my mechanical movement incorporated; 2 is a pan rigidly secured to the frame by any suitable means; 3 is a punching disk in which I have shown the movable or "eccentric" gear 3^a of my mechanical movement as being integral, though said gear may be separate and fastened to said punching disk 3.

Essentially, my mechanical movement comprises the rotary member 7 in which is rigidly mounted the drive shaft 8, a stationary or "concentric" gear 1^a (which I have shown as being integral with the frame 1, though said gear may be separate and bolted or otherwise fastened to said frame) with a mating pinion 4, a movable or "eccentric" gear 3^a with a mating pinion 5, a shaft 6 to which said pinions 4 and 5 are rigidly secured, and a crank-stud 9, which, as drive shaft 8 rotates, imparts the oscillations to the punching disk 3. I have shown a collar 10 to prevent the punching disk 3 from vertical dislodgment. A collar 17 is secured to the drive shaft 8 to hold said drive shaft and co-acting parts in proper alignment. As rotary member 7 rotates the pinion 4 is caused to rotate due to the intermeshing with the stationary or "concentric" gear 1^a. In turn pinion 5 is caused to rotate, since the pinions 4 and 5 are rigidly secured to the

shaft 6 and hence integral, and as said pinion intermeshes with the movable or "eccentric" gear 3^a, there is a similar rotary movement imparted to said movable gear, the difference in their relative velocities being controlled by the gear ratios of the gear "trains." If the ratios of the "train" 4 and 1^a and the "train" 5 and 3^a are identical there will be no actual rotary motion imparted to the disk 3, but merely an oscillatory movement due to the eccentricity of the shaft 9. The action of the stationary gear-movement (pinion 4 rotating and revolving around the gear 1^a) and the reaction of the movable gear-movement (pinion 5 rotating and revolving around the gear 3^a), in case of equal ratios, equalize each other. In practice it is desirable to have the disk 3 make about sixteen complete oscillations or "punches" for each one rotation. This punching action is necessary to "punch" the dough, and the rotary movement necessary to give the dough the "rounding" effect and cause the dough to travel around the pan 2. The direction of rotation of the disk 3 is shown by an arrow.

For an example, in the drawing the stationary gear-ratio is 112:28 (112 teeth in the gear 1^a and 28 teeth in the pinion 4) and the movable gear-ratio is 128:30 (128 teeth in the gear 3^a and 30 teeth in the pinion 5). Since 112:28 is the same ratio as 120:30, the differences between the gear ratios in the example are 4:1 and $4\frac{4}{15}:1$. The excess in the ratio is 8 in 128, or one-sixteenth; hence, the disk 3 makes but one-sixteenth the number of rotations as does shaft 8. Any desired variations of speed may be obtained to suit specific needs. As will be manifest from a study of the mechanical movement the number of rotations of disk 3 is dependent upon the difference in the gear ratios of the lower gears (4 and 1^a) and the upper gears (5 and 3^a).

In operation the disk 3 of the dough-handling machine in which my mechanical movement is shown incorporated is carried around in such a way that a point on its periphery will describe a figure, circular in the main, but having a series of inwardly curved scallops or hypocycloids, each point indicating a thrust toward the pan 2. It was found advantageous to the accomplishment of kneading to place a plurality of

tuckers 16 in the path of the dough. These tuckers are secured to the pan 2, and were the subject of Patent No. 1,087,564. The dough to be handled or rounded up is de-
5 posited in the pocket 2^a.

To operate the dough-handling machine with which I have shown incorporated my mechanical movement I have shown a gear 11 rigidly secured to the drive shaft 8, and
10 a mating gear 12 rigidly secured to the pulley shaft 13, on which is mounted the tight and loose pulleys 14 and 15, or any other suitable means of motive power. Drive shaft 8 is shown journaled in bearings 1^b and 1^c, and pulley shaft 13 is shown journaled in bearings 1^e and 1^d.

Other modes of applying the principle of my invention may be employed instead of the one explained, provided the means
20 stated by any of the following claims or the equivalent of such stated means be employed.

Having thus described my invention, what I claim as new, and desire to secure by Letters Patent, is—

1. A mechanical movement of the character described wherein revoluble and rotary movements are simultaneously imparted to a punching disk, comprising a punching disk, crank-pins means for revolving said punching disk, and multiple sets of mating gears of different gear ratios for simultaneously imparting rotary movement to said punching disk.

35 2. A mechanical movement of the charac-

ter described comprising a rotary member, a crank pin mounted in said rotary member, a gear actuated punching disk mounted on said crank pin, and multiple sets of mating gears, said punching disk being re-
40 volved by said crank pin and rotated by said multiple sets of mating gears so that a plurality of oscillatory movements for each rotary movement result.

3. A mechanical movement of the character described comprising a stationary drive gear, a punching disk journaled on a crank pin, a rotary driven gear mounted in said punching disk, a rotary member in which said crank pin is mounted, integral mating 50 pinions for said stationary drive gear and said rotary driven gear journaled in said rotary member, the gear ratios of said stationary drive gear and its mating pinion and said rotary driven gear and its mating 55 pinion being different, and all axes of rotation being parallel, for the purpose of imparting a plurality of oscillations for each rotation of said punching disk.

4. A mechanical movement of the character described comprising a rotary member, a crank pin mounted in said rotary member, integral pinions of different tooth ratios journaled therein, a stationary drive gear, a rotary driven gear, said rotary driven 65 gear being journaled on said crank pin mounted in said rotary member, and means for driving said rotary member.

BRYAN D. PINKNEY.
